UNITED STATES PATENT OFFICE.

ANDREW B. FLAGG, OF ATTLEBORO, MASSACHUSETTS.

VANITY CASE.

Application filed December 15, 1921. Serial No. 522,652.

To all whom it may concern:

Be it known that I, ANDREW B. FLAGG, a citizen of the United States, residing at Attleboro, in the county of Bristol and State of Massachusetts, have invented certain new and useful Improvements in Vanity Cases, of which the following is a specification.

This invention relates to vanity cases for women's use, and has for its object to provide such a case in which a plurality of trays or receptacles are housed in superimposed relation between its side walls, means also being provided whereby these side walls of the case may be opened or swung apart and the trays moved forward to extended position to open them and present their contents to the user.

With these and other objects in view, the invention consists of certain novel features of construction, as will be more fully described, and particularly pointed out in the appended claims.

In the accompanying drawings:

Figure 1 is a front elevation of my improved case closed or in position to be carried about.

Figure 2 is a sectional side elevation of my improved vanity case, showing the lid in dotted lines as swung back and supported in the desired operative position.

Figure 3 is an enlarged sectional elevation showing the trays as pivotally connected together and swung forward from between their housing walls to present their contents to the user.

Figure 4 is a perspective view showing the side walls as swung into open position and the trays as swung forward to open them and present their contents, in which position they cooperate with the opened side walls to provide a broad supporting base.

It is found in practice desirable to provide a portable vanity case with a plurality of trays adapted to carry different materials for treating the skin, such as powder, rouge or other materials and to arrange these trays so that those beneath are covered by those above when in closed or inoperative position and also to so arrange these trays that they may be moved forwardly and all opened simultaneously if desired to present their different contents to the user, and the following is a detailed description of one construction of vanity case

by which these results may be accomplished:—

With reference to the drawings 10 and 11 designate the two vertically-disposed side walls of the casing which are hinged together at 12, see Figure 4, on their rear sides.

These side walls may be made in any desired shape such as circular, hexagonal, octagonal or any other preferred design.

To one of these wall sections I hinge at 14 a lid or cover 15 which is the same shape as the body sections and adapted to close over the upper edges of said side walls to lock them together.

On the inner face of this lid I preferably mount a mirror 16 which may be secured by a bezel 17 or other suitable means, and on the rear of this lid I have formed a projection 9 adapted to register with the projection 18 on the rear of the wall section 10 to form a stop or rest to support the lid with its mirror in the desired operative position when the lid is open.

On the top of this lid is mounted an eye 19 to which the end member 20 of the handle 21 is connected.

Between these side walls 10 and 11 I have positioned a plurality of trays or boxes, 22, 23 and 24, the first tray 22 being permanently secured to the wall section 10 and this tray is provided at its forward edge with a downwardly-extending pivot pin 25 which is secured at its upper end to the wall 90 of the tray, its lower end extending through a short tube 26 in the second tray and is headed over at 27 at its bottom permitting this tray to swing outwardly and forwardly from beneath the first tray, 95 thereon. The second tray 23 is also provided with a similar pivot pin 28 which is connected to it at its upper end while its lower end is rotatably mounted in the tube 29 and is held in position by its enlarged 100 end 30 beneath the bottom thereof.

By this construction it will be seen that when the trays are contracted or swung back into superimposed relation between the side walls of the casing, the one above 105 serves as a cover for that below and all with the exception of the upper tray may be swung forward to be opened at once, and simultaneously present the contents of each to the user. Then again when the wall section 11 is swung laterally to open position 110 and the members of the tray are swung out

wardly into presentation position the two cooperate to greatly enlarge the supporting base to effectually prevent the case from tipping over and spilling its contents.

5. When the trays are housed between the side walls the lid may be swung forward on its hinge and upon being closed over the upper edges of the wall sections it serves to lock them securely together, and to prevent 10 this cover from accidentally opening I have provided a forwardly-projecting lip 31 on the section 11 which engages a corresponding opening 32 in the front edge of the lid thereby providing a detent which locks the 15 cover in closed position.

When it is desired to release this detent it is only necessary to press upon the button 33 which springs the wall of the front section inwardly withdrawing its lip 31 from 20 the recess 32 in the cover releasing the cover to be moved to open position.

The device is extremely simple and practical in construction and effective in its operation and by its use any desired number of 25 trays may be employed to retain a corresponding number of different materials employed by the user for toilet or other purposes.

30. The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A vanity case comprising a shell formed 40 of a pair of separable side walls, a lid for the case, and a plurality of superimposed trays housed between said walls and adapted to be moved forward from between the walls of the shell when the lid and the side walls are swung to open position.

2. A vanity case comprising a shell formed 45 of a pair of vertically-disposed hingedly-connected side walls, a lid hinged to one of the side walls and adapted to close over both sections thereof to lock them in closed position, and a plurality of superimposed trays normally mounted between said walls, one of said trays being pivotally mounted to be swung forward from closed position to present its contents to the user.

3. A vanity case comprising a shell formed 50 of vertically disposed side walls having sec-

tions hingedly connected together, a plurality of superimposed trays movably housed between said walls and pivotally connected to each other to be swung from under each other to open said trays and present their 60 contents to the user.

4. A vanity case comprising a shell formed of sections hinged together and adapted to have their front meeting edges swing apart, a plurality of superimposed trays normally 65 housed between said walls, each being pivotally connected to the one above, the upper one of said trays being fixed to one of said wall sections whereby when those below are swung forward each is opened and positioned to present its contents to the user.

5. A vanity case comprising a shell formed of vertically disposed side walls having sections separably connected together, a plurality of superimposed trays normally 75 housed between said walls and pivotally connected to each other to be swung to open said trays and present their contents to the user, and a lid adapted to close over and lock together the upper edges of said wall sections 80 when closed to house said trays.

6. A vanity case comprising a shell formed of sections hinged together and adapted to have their front edges swing apart, a plurality of superimposed trays normally 85 housed between said walls each being pivotally connected to the one above, the upper one of said trays being fixed to one of said wall sections whereby when those below are swung forward each is opened and positioned to present its contents to the user, a lid adapted to close over and lock together the upper edges of said wall sections when closed to house said trays, a mirror in the inner face of said lid, and means for supporting said lid with its mirror in the desired operative position when open.

7. A vanity case comprising a shell formed of side wall sections adapted to be swung apart to release its contents, a plurality of superimposed trays normally housed 100 between said wall sections and adapted to be moved forward to open them and also to present their contents to the user, the lower-most tray cooperating with the opened wall sections to provide an extended supporting base for the case.

In testimony whereof I affix my signature.

ANDREW B. FLAGG.
